PAULA G. PARISSETTE, OF NEWARK, NEW JERSEY

DRESS HOLDER

Application filed April 25, 1930. Serial No. 447,149.

Special objects of this invention are to provide a holder for ladies' dresses, which will support and hold the clothes in shape while confined in a suitcase or the like, and to provide a holder of this character, which will be light, inexpensive and entirely practical.

The foregoing and other desirable objects are attained in the invention by certain novel features of construction, combinations and relations of parts as set forth in the following specification.

The drawings accompanying and forming part of the specification illustrate several forms the invention may take, but it will be understood that the structure may be further modified without departure from the true spirit and broad scope of this invention.

Figs. 1 and 2 are perspective views illustrating a form of the holder in closed and open relation; Figs. 3, 4, 5, 6 and 7 are perspective views illustrating other embodiments of the invention as closed and in use.

The holders shown consist in each instance of a pair of boards or panels 6, 7, flexibly joined together as by encircling tapes or elastics 8, 9, Figs. 1, 3 and 4 or by cooperating members 10, 11 of snap fasteners as in Fig. 5.

The dress, which is indicated in a general way at 12 in Fig. 2 is placed between the boards, in properly folded condition, usually with a cardboard shape or form 13 inserted in or engaged with the same and in this condition, the boards are secured so as to hold the dress in such properly folded shape.

In Figs. 1, 2 and 3, the tapes 8 are used as the ties for securing the boards together, whereas in Fig. 4, long elastic bands 9 are used for the purpose. The ties may be guided, for instance, as shown in Figs. 1 and 2 by passing them through eyelets 14 in the boards or as in Fig. 3 by running them through loops or staples 15 on the outside of the boards.

To confine the dress or dresses at the sides and ends of the holder, flexible flaps 16, 16, and 17, 17, may be attached to or extend from the side and end edges of one of the boards, the bottom one shown in Fig. 2, which may be folded inward in the manner

shown to hold and cushion the dress material.

The confining flaps may also be utilized as part of the means for flexibly securing the boards together as indicated in Fig. 5, where the side and end flaps 16a, 16a and 17a, 17a, are shown as carrying the button members 10 of the snap fasteners to engage with different sets of post members 11 on the top board. It will be understood from this view, that one set or a number of sets of the snap fasteners may be provided, depending on whether the holder is intended to be one special size or to be expandible to accommodate itself to different thicknesses of material.

In the fully closed condition, such as shown in Figs. 1, 3, 4 and 5, the dress is entirely enclosed and hidden. For the purpose of identification, a small holder 18 may be provided on the top board into which a dress identifying card may be slipped as in Figs. 1, 3, 4 and 5.

The boards or panels may be made of any suitable light and fairly stiff material, such as cardboard, fiber-board or the like. It has been found most practical to make them of a size slightly larger than the folded outline of an average size dress, as such a size will hold the dress in shape without confining it too closely and at the same time will easily fit in an ordinary size suitcase. One or several dresses may be placed in each holder, the flexible or expandible character of the holder permitting this. This construction also enables cushioning material being placed in the dress to hold it better in shape. The side and end flaps prevent the dress from slipping about in the holder, so that the holder need not be fastened so closely as to press creases in the dress. It is usually preferred to use one holder for each dress, so that the packing and unpacking of one will not disturb any other. With the identifying names on the outside, the holders may be packed in any desired order resting flat one on the other and because of the greater orderliness, occupying no more or even possibly less space in a suitcase than dresses loosely packed in the usual way. The holders confine and secure the dresses with-

out crushing them and retain them in shape even when subjected to the jarring and vibration of long automobile trips.

Instead of being connected by flexible tapes or the like, the boards may be flexibly hinged together along one edge as by a bellows hinge, such as will readily permit of the expansion and contraction adjustments to accommodate dresses of different thicknesses. Fiber-board 5 is particularly suitable for the panels, because in addition to being thin, relatively stiff but flexible, it is smooth, water-proof and not affected by heat. The latter attribute is particularly important as such boards in effect 10 "insulate" the dresses against the harmful temperature effects resulting from confinement in a suitcase during long periods of automobile travel, it being recognized of course that temperature is a factor in the pressing and creasing of clothes. The flaps about the sides of the lower board may be of suitable fabric and these parts as well as the boards themselves may be of ornamental design, color or finish, so that the clothes packages in 15 themselves will present an attractive appearance.

Other changes and modifications may be made within the scope of the claims broadly covering the invention and the invention may 20 be put to other purposes than strictly to carrying ladies' dresses.

The forms of the invention shown in Figs. 6 and 7 are somewhat lighter and less expensive than those first described. Thus in Fig. 35 6, the securing tapes or cords 8 are located by passing them through the loops 15a provided by cutting parallel slits 19 in the boards and slightly offsetting the material between these slits. In Fig. 7, a similar effect is ac- 40 complished by punching closely related holes 19a in the boards to provide the intermediate bridging portions 15b serving as loops for the cords.

What is claimed is:

45 1. A holder for transporting a lady's dress in a suitcase or the like, and comprising a pair of thin, flat, light, stiff, smooth and flexible boards of sufficient width and length to accommodate between them a lady's dress in 50 properly folded relation, one board having flexible fabric flaps extending from the edges of the same and foldable inwardly over a dress placed on said board, the other board being separable from said first board out of 55 the way of adjusting a folded dress on the first board and of the turning in of the flaps over the thus positioned dress and readily releasable means for confining the second board over the turned in flaps of the first board, said means being quickly releasable and adjustably secured the boards together 60 at different points in the length of the same to thereby reinforce and form a compact self-supporting packet as thin as the character of 65 the dress will permit.

2. A holder for transporting a lady's dress in a suitcase or the like, and comprising a pair of thin, flat, light, stiff, smooth and flexible boards of sufficient width and length to accommodate between them a lady's dress 70 in properly folded relation, one board having flexible fabric flaps extending from the edges of the same and foldable inwardly over a dress placed on said board, the other board being separable from said first board 75 out of the way of adjusting a folded dress on the first board and of the turning in of the flaps over the thus positioned dress and readily releasable means for confining the second board over the turned in flaps of the 80 first board, said means being quickly releasable and adjustably securing the boards together at different points in the length of the same to thereby reinforce and form a compact self-supporting packet as thin as the character of 85 the dress will permit, the turned in flaps serving to cover and protect the edges of a folded dress between the boards and identifying means on one of the boards for the folded dress thus concealed by 90 the edge flaps.

In testimony whereof I affix my signature.
PAULA G. PARISSETTE.
